His Attorney,

UNITED STATES PATENT OFFICE.

CHARLES L. HEISLER, OF SCHENECTADY, NEW YORK, ASSIGNOR TO GENERAL ELECTRIC COMPANY, A CORPORATION OF NEW YORK.

GEARING.

Application filed February 10, 1921. Serial No. 443,920.

To all whom it may concern:

Be it known that I, CHARLES L. HEISLER, a citizen of the United States, residing at Schenectady, in the county of Schenectady, 5 State of New York, have invented certain new and useful Improvements in Gearing, of which the following is a specification.

The present invention relates to gearing and is applicable to either speed reduction or 10 multiplication gearing. The more usual application, however, is for speed reduction and the invention is accordingly particularly described as a reduction gearing. It will be understood, however, that it is not 15 necessarily limited thereto.

The object of my invention is to provide an improved structure and arrangement in a gearing, particularly the casing thereof, and for a consideration of what I believe to 20 be novel and my invention, attention is directed to the accompanying description and the claims appended thereto.

In the drawing, Fig. 1 is a side elevation, partly in section, of a gearing embodying my 25 invention, the section being taken on line $y-y$; Fig. 2; Fig. 2 is a sectional view taken on line $x-x$; Fig. 1 and Figs. 3, 4, 5, 6 and 7 are perspective views illustrating the 30 casing structure and the parts which go to make up the same.

In the present instance my invention is illustrated in connection with a reduction gearing comprising a driven gear wheel 10 mounted on a shaft 11 and driven by two 35 sets of gears located on opposite sides of gear wheel 10. Each gear set comprises a high speed driving pinion 12 carried by a shaft 13 and meshing with a gear wheel 14 on shaft 15, which shaft carries also a low 40 speed pinion 16 meshing with two gear wheels 18 loosely mounted to turn on fixed shafts 19 and in turn meshing with low speed gear wheel 10. The gearing illustrated is of the double helical type, the two 45 halves of pinion 12 and gear wheel 14 being spaced apart and pinion 16 and gear wheels 18 being located between them. This gives a compact symmetrical arrangement. Gear wheels 18 serve as intermediates to transmit 50 the load in parallel from pinion 12 to driven gear wheel 10, the load being equally divided between them.

Referring now to the casing, it comprises a rectangular base 20 in the form of a box

having transversely extending webs 21 to 55 give it strength and rigidity. The top and bottom walls are indicated by reference numerals 22 and 23, the end walls by numeral 24, and the side walls by numeral 25. The lower surface of the bottom wall is provided with pads 26 which are finished and which serve to support the casing on a foundation, and at the two ends of the base are bolting flanges 27 provided with bolt holes 28. Projecting upwardly from base 20 60 are two uprights 29 located one on each side of the base midway between its ends. Uprights 29 are of box structure also, and are preferably formed integral with the base. They are provided with recesses 30 extending 65 downward from their tops. The bottoms of the recess, as indicated at 31, are curved to receive bearing linings. The end faces of uprights 29 are provided with finished surfaces 32, the uprights being preferably provided with flanges 33 in order to increase the 70 width of such faces, and around the margins of the ends of base 20 are pads 34 having finished surfaces of the same width as surfaces 32. Pads 34 preferably project beyond the outer edges of base 20 to provide 75 flanges which contain bolt holes 35.

Curved surfaces 31 of the uprights are adapted to support the shaft of the driven gear wheel, in the present instance shaft 11 80 which carries gear wheel 10, and when the shaft is in place, a cap 36 having projections 37 as shown in Fig. 4, is put into place, the 85 projections fitting into recesses 30. Cap 36 and projections 37 are of rectangular box 90 structure and the lower ends of projections 37 are curved as indicated at 38 to receive the upper halves of the bearing linings.

On each side of uprights 29 there is a space, as best shown at the right hand side of Fig. 3, for the remaining gear wheels of the gearing and I support the shafts for such gear wheels by means of a built-up structure made from box-like members of rectangular section. The shape and size of 100 these members will vary according to the specific nature of the gearing, the number of shafts to be supported, and the distance between shaft centers. In the gearing illustrated, there are four shafts to be supported 105 and I accordingly provide two lower members 40 and 41, two upper members 42 and 43, and an intermediate member 44. Mem-

bers 40, 41, 42 and 43 are substantially alike in structure, the general structure of each being illustrated in Fig. 5. Each comprises a rectangular end piece 45 having two side pieces 46 and 47 formed integral with it. The end and side pieces are of box-like structure and rectangular in section, and the side pieces are provided with curved transverse recesses 48 to form supports for the shafts. They are also provided with suitable bolt holes 49. Intermediate member 44 is shown in perspective in Fig. 6 and comprises an end piece 50 and two side pieces 51 all of rectangular, box-like structure. It is provided with shaft openings 52 and 53 in which are bearing linings 54.

In assembling the gearing, lower members 40 and 41 are put into place as shown at the left hand side of Fig. 3, lower shaft 19 with gear wheel 18 thereon being clamped in recesses 48. The intermediate member 44 is then put into place, shaft 13 with pinion 12 thereon, and shaft 15 with pinion 16 and gear wheel 14 thereon, being mounted in bearings 52 and 53 respectively. In the case of shaft 13, it will be noted from Fig. 2, that opening 52 is of greater diameter than pinion 12, so shaft 13 can be slipped into place axially, the bearing linings, which may be made in halves, being put into place afterwards. In the case of shaft 15, the side pieces 51 of member 44 may be split on the vertical plane through the center of openings 53 as indicated at 55 to permit of assembling the shaft in the bearings, suitable bolts passing through openings 56 being provided to hold the parts together so member 44 is in substance a unitary structure. Upper members 42 and 43 are then put into place, upper shaft 19 with gear wheel 18 thereon being clamped in recesses 48. The entire built-up structure is then bolted together to form a rigid unit. The general arrangement of bolts is shown in the drawing but it will be understood that such bolts may be used as found desirable to fit the needs of any particular case.

In order to get shafts 15 into correct vertical alignment with shafts 19 it is desirable to be able to slightly shift or adjust intermediate member 44 relatively to members 40, 41 and 42, 43. For this purpose I provide faces 32 with transverse grooves 57 in line with intermediate member 44, and in member 44 I provide openings 58 in which are bushings 59 of a length slightly greater than the thickness of member 44 so their two ends project very slightly beyond the surface of member 44. The projection of the ends of bushings 59 beyond the surface of member 44 may be of the order of .0015 inch for example so when the various members are mounted in place as shown in Fig. 3, intermediate member 44 will be spaced slightly from the adjacent members. This will per-

mit it to be moved without too much friction, and when in correct position, the tightening of the bolts will hold it.

On top of the gear casing are cover plates 60 suitably bolted into place. They are preferably provided with strengthening ribs 61 which serve to make the covers more rigid and to brace the casing as a whole.

In the specific arrangement of gearing illustrated, the side pieces of members 41, 44 and 42 are of less width than the side pieces of members 40 and 43 to provide space for the accommodation of gear wheels 14, and the end piece 50 of member 44 is cut back as indicated at 62 in Fig. 6 to permit gear wheels 14 to mesh with pinions 12. This arrangement serves to give a smooth exterior to the gear casing and a compact arrangement of maximum strength.

When the gearing is assembled and bolted together a very strong rigid casing structure or supporting structure results which is able to maintain the gear wheels in correct alignment at all times and under severe usage. All the casing members are formed of rectangular box-like parts which give the maximum rigidity for a given weight and when the casing is fastened to a foundation, shifting movement of the foundation will not throw the gear wheels out of alignment. This is a matter of particular moment when the gearing is used in connection with ship propulsion since the gear casing may be subjected to considerable strains due to weaving of the ship's hull.

In connection with gear wheels 18, these wheels run loosely on shafts 19 and act as idlers to transmit the load from pinion 16 to driven gear wheel 10. Shafts 19, therefore, require no bearings in the gear casing as they are fixed against rotation. Since they require no bearings, they can be very accurately located so as to bring gear wheels 18 into correct positions. Also by eliminating two bearings I am enabled to reduce the cost of the gearings.

A feature of great utility in my invention is that the same general gear casing parts or members are adapted for use in building up gearings of various types and for various speed reductions. As is obvious the base member and uprights may support a driven gear wheel of desired size and on either one or both sides of it may be built up a driving gear arrangement using such sized members for supporting the shafts as required and with their shaft openings properly spaced and located. The machine work required is all of a simple nature capable of being performed with great accuracy. The surfaces of the various parts can be finished and fitted to each other to give exact location of the gear wheel centers so when assembled the gear wheels will mesh correctly. In this connection it is to be noted that if after

the gearing is assembled, the wheels do not mesh correctly or any one slightly off-centers various surfaces can be easily shaped to bring the wheels to exact meshing position.

The arrangement shown in the drawing is for a double drive and in use a prime mover, such as an elastic fluid turbine may be connected to each of the driving shafts 10 13. Turbine shafts are indicated at 64 and 65.

In accordance with the provisions of the patent statutes, I have described the principle of operation of my invention, together 15 with the apparatus which I now consider to represent the best embodiment thereof, but I desire to have it understood that the apparatus shown is only illustrative and that the invention may be carried out by 20 other means.

What I claim as new and desire to secure by Letters Patent of the United States, is:—

1. In a gearing, the combination of a base, uprights carried by the base and spaced 25 from one end of it, a gear wheel carried by said uprights, a plurality of supporting and spacing members mounted on the end of said base and fastened to it and said uprights, said members being horizontally divided 30 and built up one above another to form a unitary construction, and a gear wheel arrangement carried by said members and cooperating with said gear wheel.

2. In a gearing, the combination of a base, uprights carried by the base and spaced from one end of it, a gear wheel carried by said uprights, a plurality of box-like supporting members rectangular in section mounted on said base and fastened to 35 it and said uprights, said members being horizontally divided and built up one above another to form a unitary construction, and gearing carried by said members and meshing with said gear wheel.

4. In a gearing, a base of box structure, uprights of box structure on opposite sides of the base and spaced from one end, and members of box structure horizontally divided and mounted one above another on 40 such end, said members forming a unitary construction in conjunction with said uprights to support, space and locate a gearing.

5. In a gearing, a base of box structure, uprights of box structure on opposite sides of the base and spaced from one end, upper, 45 low and intermediate members of box structure mounted on such end and fixed to the

base and uprights, certain of said members being adjustable in a plane parallel to the 60 base, and gearing carried by said uprights and members.

5. In a gearing, the combination of a base, uprights on opposite sides of the base midway between its ends, horizontally divided supporting members mounted one above another on the ends of said base and fastened to it and the uprights to form a supporting and spacing unit of interchangeable parts, and gearing carried by said uprights and supporting members.

6. In a gearing, the combination of a base of box structure, uprights of box structure on opposite sides of the base midway between its ends, a shaft carried by said uprights, a gear wheel on said shaft, horizontally divided supporting members of box-like structure mounted one above another on the ends of the base and fastened to the base and said uprights, and gearing carried 70 by said supporting members and cooperating with said gear wheel.

7. In a gearing, the combination of a base of box structure, uprights of box structure on opposite sides of the base midway between its ends, lower, upper and intermediate members of box structure mounted on said base ends and fastened thereto and to the uprights, a gear wheel carried by said uprights, gear wheels carried by said upper and lower members which mesh with said first named gear wheel, and a pinion carried by said intermediate member and meshing with said second named gear 85 wheels.

8. A gear casing built up from a plurality of interchangeable gear and pinion supporting members of box structure mounted one above another to form a unitary construction and a common base upon which 90 said combination is supported.

9. A gear casing comprising a base and a plurality of supporting members thereon of box structure, said members being horizontally divided and built up one above another 95 to form a unitary construction.

10. A gear casing comprising a base of box structure, uprights of box structure on the base, and horizontally divided supporting members of box structure mounted one 100 above another and fastened to the base and uprights.

In witness thereof, I have hereunto set my hand this 9th day of February, 1921.

CHARLES L. HEISLER.
